(57) **ABSTRACT**

An inkjet printing method on a continuous substrate web (100), having a pair of edges (1011, 1021), comprising the steps: a) forming a pair of elongated strips (101, 102) by bending said substrate web (100) along a pair of lines (1010, 1020) wherein each line is parallel to the pair of edges (1011, 1021); and b) supporting said bent substrate web in a support zone (201) of a printer (200) wherein said pair of elongated strips (101, 102) are oriented below said zone (201); and printing an image (500) on said supported substrate web by an inkjet-printhead (202) of said printer (200).

INKJET PRINTING METHOD FOR MANUFACTURING A DECORATIVE SURFACE

CROSS-REFERENCE TO RELATED APPLICATIONS

This patent application is the U.S. national phase of copending International Patent Application No. PCT/EP2021/065229, filed Jun. 8, 2021, which claims the benefit of European Patent Application No. 20181011.6, filed Jun. 19, 2020.

TECHNICAL FIELD

The present invention is an inkjet printing method on a continuous substrate web, especially light-weight continuous substrate web, having edge-waviness.

BACKGROUND ART

Inkjet printing methods on continuous substrate web (100) are already explored for several decennia not only by multi pass printing but also by single pass printing wherein the continuous substrate web (100) is transported by web-fed roll-to-roll process or web-fed roll-to-sheet process. Said substrate web (100) is transported by unwinding a roll of said substrate web (100), the so-called input roll (111), before it is supported in a support zone (201) of the printer. After printing, the substrate web may be cut into sheets or may be rewinded on another roll, the so-called output roll (112). Continuous substrate web is typically light-weight material which can be wound on a roll for printing. It can be bend easily around a core. The printer has means for supporting said input roll (111) and optionally said output roll (112) and is configured for transporting the substrate web (100) underneath the inkjet-printhead (202).

Said methods tried to solve known issues when using inkjet print technology on a continuous substrate web (100) which cause inferior print quality:

irregular transport speed of said substrate web (100);
web swim of said substrate web (100);
stretch or shrink of said substrate web (100) while printing; drying and/or transporting due to changing of internal forces in said substrate web (100).

Examples of said methods are applied in the following printers:

Agfa Dotrix Modular by manufacturer AGFA NV;
KBA Rotajet by manufacturer Koenig & Bauer AG;
Rho 312R Plus/LED by manufacturer Durst Phototechnik AG;

Gallus Labelfire 340 by manufacturer Heidelberg Druckmaschinen Aktiengesellschaft.

Another issue is the non-flatness at the edges (1011, 1021) of a continuous substrate web (100) while transporting said substrate web (100) underneath an inkjet-printhead (202) of a printer (200). Said non-flatness occur after unwinding the substrate web (100) and transporting towards the support zone (201) and is the result of a previously rewinding of the input roll (111), previously cutting a big roll in smaller rolls, storage-conditions of the input roll (111), internal forces in the substrate web (100) that changes after unwinding; lower internal forces at the edges than in the middle of the substrate; humidity of the input roll (111) and/or humidity at the printing room. Said non-flatness is sometimes called edge waviness.

U.S. Pat. No. 9,682,573 BB (XEROX CORPORATION) discloses a method wherein said non-flatness at the edges (1011, 1021) is first calendered before printing for having a total flat substrate web. It is found that this is not feasible for any type of material of the substrate web.

Said non-flatness may cause also that the holding down of the substrate web (100) against the support zone (201) of the printer (200) is not optimal, which may result in crashes of the substrate web (100) against an inkjet-printhead (202) of the printer (200) and creating wrinkles in said substrate web (100) during its transport through the printer (200).

SUMMARY OF INVENTION

15 It is an object of the present invention to provide a solution for an excellent holding down of a substrate web (100), having edge-waviness, so no wrinkles in said substrate web (100) can occur during the transport underneath an inkjet-printhead (202) of the printer.

20 This object has been realised with the inkjet printing method as defined in claim 1.

Further objects of the invention will become apparent from the description hereinafter.

BRIEF DESCRIPTION OF DRAWINGS

FIGS. 1 to 5 are cross-sections of an inkjet printer (200) of preferred embodiments with at the left-side the entrance of substrate web (100) from an input roll (111).

30 FIG. 6 is a cross-section of a preferred printer (200) which illustrates how a bend substrate web (100) is applied on the support zone (201).

FIGS. 7 to 9 are images of a preferred edge-bender unit (203).

35 FIGS. 8 and 9 show also a substrate web (100) which is bended by the edge-bender unit (203). Said bending is illustrated by the black small arrow. At the other edge of the substrate web (100) there is a similar edge-bender unit (204) in the printer (200). It is a mirrored version. Said mirrored version is not shown in said images.

FIGS. 10 and 11 illustrate the edge-bender unit of FIGS. 7 to 9. FIG. 11 is an unassembled edge bender unit.

FIG. 12 illustrates how the substrate web (100) is bended in a top-view of a preferred printer (200) namely a single pass inkjet-printer with an elongated inkjet-printhead (202) positioned over the substrate web (100).

FIG. 13 illustrates how the substrate web (100) is bended in a top-view of a preferred printer (200) namely a multi pass inkjet-printer with an inkjet-printhead (202) positioned over the substrate web (100) which is configured to move across the substrate web (100).

DESCRIPTION OF EMBODIMENTS

55 The present invention is an inkjet printing method on a continuous substrate web (100), having a pair of edges (1011, 1021), comprising the steps:

a) forming a pair of elongated strips (101, 102) by bending said substrate web (100) along a pair of lines (1010, 60 1020) wherein each line is parallel to the pair of edges (1011, 1021); and

b) supporting said bent substrate web in a support zone (201) of a printer (200) wherein said pair of elongated strips (101, 102) are oriented below said zone (201); and printing 65 an image (500) on said supported substrate web by an inkjet-printhead (202) of said printer (200). Thus the elongated strips (101, 102) are not supported by the support zone

(201). So instead of flattening the pair of edges (1011, 1021) before printing as known in the state-of-the-art, the pair of edges are bend before printing. In said invention the material of the substrate web (100) between the pair of lines (1010, 1020) is in contact with said support zone (201).

As shown in FIG. 6 the substrate web (100) is applied on the support zone (201), here located on a vacuum belt (250) wherein a vacuum table (253) is used to provide vacuum power in said support zone (201) via a vacuum chamber (255). Before the application on said support zone (201), the edges (1011, 1021) are bended and oriented below said support zone (201) after application on said support zone (201). Elongated strips (101, 102) are formed along a line (1010, 1020), with a determined bending angle (2010). Said lines are also called bending lines.

The elongated strips (101, 102) are hereby also oriented underneath the substrate web (100) between said strips (101, 102) when the substrate web (100) is supported. This can be done by bending the substrate web (100) with a bending angle larger or equal than 90 degrees. Thus the bending is not folding which results then in a bending angle of 0 degrees.

The elongated strips (101, 102) are preferably flanking a support means whereon the support zone is located. The support means are for example a conveyor belt or a printing table.

The elongated strips (101, 102) are applied by bending the substrate web (100), each by an edge bender unit (203, 204) and they are further oriented below the support zone (201) when the substrate web is supported on said zone (201). Hereby the substrate web is positioned more stable on said zone (201). The pair of lines (1010, 1020) formed after the step a) gives a higher stiffness in said substrate web and the elongated strips (101, 102) behave like a pair of flanges which are positioned outside the support zone and more precisely below the support zone.

The material of the substrate web (100) should of course be pliable which is mainly so for light-weight substrate web which has a weight below 150 g/m² more preferably below 120 g/m² and above 10 g/m². If the material of said substrate web comprises fibers, such as cellulose fibers, the pair of lines (1010, 1020) are preferably substantially parallel to the orientation of said fibers for easy bending and for avoiding that the fibers break. The substrate web (100) may of course also be a polymeric substrate. The width of the substrate web is preferably more than 1 m. Said width is measured as shortest distance between the pair of edges (1011, 1021).

In the present disclosure is the substrate web between the elongated strips (101, 102) supported on the support zone (201).

Preferably the smallest angle between the support zone (201) and each elongated strip of the pair of elongated strips (101, 102) is below 160 degrees when the continuous substrate web (100) is supported in said zone (201). Said smallest angle is more preferably between 0.1 and 145 degrees and most preferably between 2 and 100 degrees. Said degree depends on the material of the substrate web (100) and how large the stiffness is caused by said down oriented elongated strips (101, 102) on the support zone (201).

In a preferred embodiment the width of each elongated strip of the pair of elongated strips (101, 102) is below 10 cm. Said width is more preferably between 1 mm and 70 mm and most preferably between 2 mm and 40 mm. Said width is selected by the operator of the printer (200) but it is mainly chosen depending material of the substrate web (100) and/or how large the stiffness is caused by said down oriented

elongated strips (101, 102) on the support zone (201). Said width is the shortest distance between the line (1010, 1020) of the elongated strip (101, 102) and the edge (1011, 1021) is part of said elongated strip (101, 102).

5 In a preferred embodiment the inkjet printing method is a single pass inkjet printing method (FIG. 12).

In a preferred embodiment step b) comprises the step(s): applying vacuum below the support zone (201) for holding the pair of elongated strips (101, 102) below said zone (201); and

10 optionally applying vacuum for holding down the supported substrate web towards said zone (201) for example by a vacuum belt (250) of a preferred printer (200) for transporting the substrate web (100) underneath the inkjet-printhead (202). Instead of a vacuum belt (250) also a vacuum table (253) of the printer (200) may be used. Said vacuum belt (250) or vacuum table (253) is hereby a supporting means of the printer (200) whereon said the support zone (201) is located.

15 In another preferred embodiment step b) comprises the step

blowing air for holding the pair of elongated strips (101, 102) below the support zone (201); or guiding the pair of elongated strips (101, 102) for holding them below the support zone (201) by guiding means such as rolls or gliders.

20 If the support zone (201) is part of a vacuum belt (250) in the supporting step of step b) additionally may apply a part of each elongated strips (101, 102) at an opposite side of the support zone (201).

25 FIG. 11 and FIG. 12 illustrate the bending of the edges (1011, 1021) of the substrate web (100) as a preferred embodiment of the disclosure wherein the edges (1011, 1020) remains bended (2000) by the edge bender units (203, 204) and hereby forming a line (1010, 1020) and elongated strips (101, 102) while printing and they (101, 102) may be flattened after printing.

Polymeric Substrate

30 Any polymeric substrate having a maximum value for Tan 6 between 40° C. and 110° C. is suitable as web-like polymeric substrate for use in the present invention. Polyethylene is the most preferred polymeric substrate for use as web-like polymeric substrate in the present invention.

35 Polyethylene is produced in various low and high densities. These are well-known to a skilled person in manufacturing polyethylene films and foils by their abbreviations, such as UHMWPE, HDPE, PEX, MDPE, LLDPE, LDPE and VLDPE. The latter three are most commonly used for making plastic bags.

40 LLDPE is defined by a density between 0.915 and 0.925 g/cm³ and is a substantially linear polymer, with significant numbers of short branches, commonly made by copolymerization of ethylene with short-chain alpha-olefins (e.g. 1-butene, 1-hexene, and 1-octene). LLDPE has higher tensile strength than LDPE and exhibits higher impact and puncture resistance than LDPE.

45 LDPE is defined by a density between 0.910 and 0.940 g/cm³. LDPE has a high degree of short and long chain branching, which means that the chains do not pack into the crystal structure as well. It has therefore less strong intermolecular forces as the instantaneous-dipole induced-dipole attraction is less. This results in a lower tensile strength and increased ductility. LDPE is created by free radical polymerization. The high degree of branches with long chains 50 gives molten LDPE unique and desirable flow properties.

55 VLDPE is defined by a density between 0.880 and 0.915 g/cm³ and is a substantially linear polymer, with high levels

of short chain branches, commonly made by copolymerization of ethylene with short-chain alpha-olefins (e.g. 1-butene, 1-hexene, and 1-octene). VLDPE is most commonly produced using metallocene catalysts due to the greater co-monomer incorporation exhibited by these catalysts

The polymeric substrates for use as web-like polymeric substrate in the present invention are preferably selected from the group consisting of LLDPE, LDPE and VLDPE. Most preferably the polymeric substrate for use as web-like polymeric substrate in the present invention is LDPE.

The thickness of the polymeric substrate depends on the specific application. For plastic bags, preferably a thickness between 30 and 200 μm , more preferably between 50 and 100 μm and most preferably between 60 to 80 μm is used.

Sometimes, a primer layer is applied to the polymeric substrate for creating a specific effect such as a glossy or a mat finish. As long as the dry thickness is less than 5 μm , preferably less than 3 μm , these primers have no influence on the invention. The primer can be applied beforehand, for example, as a continuous layer by coating or flexographic printing. In a preferred embodiment, the primer is then a non-aqueous radiation curable liquid.

The present disclosure (the printing method) with said polymeric substrate as substrate web (100) may also be part of manufacturing decorative plastic bags.

Edge Bending

In a preferred embodiment the printer (200) comprises for forming each elongated strip (101, 102) a separate edge bender unit (203, 204).

Each edge bender unit (203, 204) is preferably used after the unwinding of the substrate web (100) and before applying said substrate web (100) on the support zone (201) of the printer (200). Hereby no wrinkles occur during the transport of the substrate web (100).

In a preferred embodiment the inkjet printing method comprises a step for controlling the width of one of the pair of elongated strips (101, 102) for example by:

moving an edge bender unit of said pair of edge bender units (203, 204) across the continuous substrate web for controlling the width of one of the pair of elongated strips (101, 102). The position of the edge bender may hereby also be adapted according to the width of the substrate web. The printer (200) is configured to make this moving possible. Thus it may be a gantry attached to said printer (200) which is positioned across the continuous substrate web whereon both edge bender units (203, 204) are movable attached for example along a rail in said gantry.

An edge bender unit (203, 204) preferably comprises a staggered pair of sliding means (2031, 2041, 2032, 2042) for bending the continuous substrate web (100) between said staggered pair of sliding means (2031, 2041, 2032, 2042) which comprises a support sliding means (2031, 2041) for supporting said substrate web (100) and a bending sliding means (2032, 2042) for applying a pressure towards said substrate web (100) along said support sliding means (2032, 2042). The sliding means (2031, 2041, 2032, 2042) in the edge bender unit (203, 204) are preferably rolls, more preferably rotatable rolls which are rotating while passing the edge of the substrate web (100) through the edge bender unit (203, 204). This minimizes damage on the surface of the substrate web (100).

Figures from 7 until 11 illustrates such a preferred edge bender unit.

In a preferred embodiment the inkjet printing method comprises step(s) for controlling the bending angle at the one of the pair of elongated strips (101, 102) by the edge bender unit:

- 5 moving the bending sliding means (2032, 2042) towards the substrate web (100) along the support sliding means (2032, 2042) in a direction;
- 10 and/or
- moving said bending sliding means (2032, 2042) towards said support sliding means (2032, 2042) in another direction.

With a handle (20321) as shown in the Figures from 7 until 11 the bending sliding means (2032) can be moved towards the substrate web (100). This is shown as a white arrow. Here also the edge bender unit (203) may move along a rail or gantry as shown by the long black arrow. Printer

The printer (100) from the present disclosure is a digital printer wherein a non-contact printing technology is used with an inkjet-printhead (202). Said printer is also called inkjet printer.

For having a good image quality, a constant height between an inkjet-printhead and ink-receiver, here a continuous substrate web (100), is needed. In the present disclosure said inkjet printer may be a multi pass inkjet printer (FIG. 13) but a single pass inkjet printer is preferred (FIG. 12). One of the big issues in inkjet printing is that ink receiver may touch the inkjet-printhead (202) whereby the inkjet-printhead is broken or has non-jetting nozzles which have to be recuperated. If the height between an inkjet-print an inkjet-printhead and ink-receiver needs to be constant, the ink receiver have to be flat or may not warp up or may not move upwards from the support zone (201).

Figures from 1 to 5 illustrates several configurations of preferred printers, wherein a substrate web (100) is applied on a support zone of the printer and wherein an edge (1011) is bended towards said support zone by an edge bender unit (203). Hereby an elongated strip (101) is formed along a line (1010) and oriented below the support zone. The substrate web (100) is unrolled from an input roll (111) and rolled after printing an image by an inkjet-printhead (202) on an output roll (112) or cutted in sheets as shown in FIG. 2 wherein the substrate web (100) is cutted by a cutter (285) and sheets are collected in an output tray (290).

FIG. 1 and FIG. 2 illustrate each a printer (200) with a vacuum belt (250) which wraps two pulleys (270). The support zone has a vacuum zone which is formed by vacuum power from a vacuum chamber (255) via a vacuum table (253). Said vacuum power brings the substrate web (100) towards the support zone as shown by the vertical black arrow. The arced black arrows show the movement of the different rolls in the printer (200).

FIG. 3 illustrates a conveyor belt printer whereby the bended substrate web (100) is flattened by a flattener (280) after the image (500) is printed.

FIG. 4 illustrates a web printer whereby the substrate web (100) is conveyed over a vacuum table (253) which forms a support zone with vacuum power from a vacuum chamber (255). Said vacuum power brings the bended substrate web (100) towards the vacuum zone before printing.

The image is preferably printed with one or more pigmented inkjet inks which may be selected from aqueous pigmented inkjet inks, solvent based pigmented inkjet inks and radiation curable pigmented inkjet inks.

65 The one or more pigmented inkjet inks preferably contain organic colour pigments as they allow for obtaining a high colour gamut on the substrate web (100). Carbon black and

titanium dioxide are inorganic pigments, which can be advantageously used in the present disclosure for composing black respectively white pigmented inkjet inks.

In a preferred embodiment, the one or more pigmented inkjet inks form a CMYK(W) or CRYK(W) inkjet ink set. The latest inkjet ink set is an advantage for printing wood colors, especially when manufacturing decorative surfaces.

Pigment particles in inkjet inks should be sufficiently small to permit free flow of the ink through the inkjet-printing device, especially at the ejecting nozzles. It is also desirable to use small particles for maximum colour strength and to slow down sedimentation. The numeric average pigment particle size of an organic colour pigment and an inorganic black pigment is preferably between 0.050 and 1 μm , more preferably between 0.070 and 0.300 μm and most preferably between 0.080 and 0.200 μm .

In a preferred embodiment the image is dried after or while printing the image on the continuous substrate web (100), said image is dried by a radiating device. The radiation may be performed by using a UV bulb lamp or a plurality of UV light emitting diodes or any type of IR-driers.

The printer maybe performing the inkjet printing method on more than one continuous substrate web (100). An example of such a printer is disclosed in WO2019/170456 (AGFA NV) which is part of manufacturing line for manufacturing decorative surfaces.

A preferred inkjet-printhead (202) for the printer (200) is a piezoelectric head. Piezoelectric inkjet printing is based on the movement of a piezoelectric ceramic transducer when a voltage is applied thereto. The application of a voltage changes the shape of the piezoelectric ceramic transducer in the printhead creating a void, which is then filled with inkjet ink or liquid. When the voltage is again removed, the ceramic expands to its original shape, ejecting a drop of ink from the inkjet-printhead.

A preferred piezoelectric printhead is a so called push mode type piezoelectric printhead, which has a rather large piezo-element capable of ejecting also high viscous inkjet ink droplets. Such an inkjet-printhead is available from RICOH^{TM} as the GEN5s printhead.

A preferred piezoelectric print head is a so-called through-flow piezoelectric drop-on-demand printhead. Such an inkjet-printhead is available from TOSHIBA TECT^{TM}, as the CF1ou printhead, and also from RICOH^{TM} and XAAR^{TM}. Through-flow printheads are preferred in the present invention, because they enhance the reliability of inkjet printing.

The support zone (201) is part of a support means of the printer (200) which is preferably a vacuum table (253) and more preferably a vacuum belt (250). On said table or belt a vacuum zone is applied as support zone (201) for holding down ink receiver with vacuum from a vacuum chamber (255) of the printer (200). For example, WO2016/071122 (AGFA GRAPHICS NV) discloses details of a printer with a vacuum belt (250).

The support zone (201) may also be formed by a plurality of rolls where over the substrate web (100) is transported for printing as for example can be found in an Agfa Dotrix Modular by manufacturer AGFA NV and probably other single pass inkjet printers. An embodiment of a preferred printer with said plurality of rolls (256) is shown in FIG. 5.

After printing the image, the pair of elongated strips (101, 102) may be flattened again for further processing of the printed substrate web (100). Thus after the bending of the substrate web, the substrate web is again flattened which may be performed by (heat-)rubbing the elongated strips (101, 102) and/or by (heat-)pressing the elongated strips

(101, 102) especially at the pair of lines (1010, 1020). Hereby the pair of elongated strips (101, 102) are spread. Said flattening is performed by a flattener (280) in Figures from 1 to 5. For faster spreading said strips vacuum may optionally be applied.

Spreading of the elongated strips (101, 102) means in the present invention that the bend angle is enlarged back to substantially 180 degrees.

Manufacturing Decorative Surfaces

The inkjet printing method of the present disclosure and all its preferred embodiments are preferably for manufacturing a decorative surface

wherein the continuous substrate web (100) is a paper substrate which has a weight less than 150 g/m² and the image is printed with one or more aqueous pigmented inkjet inks; or

wherein the continuous substrate web (100) is a thermoplastic substrate which has a weight less than 150 g/m² and which is based on a material selected from the group consisting of polyvinylchloride (PVC), polypropylene (PP), polyethylene (PE), polyethylene-terephthalate (PET) and thermoplastic polyurethane (TPU) and combinations thereof and the image is printed with one or more UV curable inkjet inks.

Said latest type of continuous substrate web is for example ideal for manufacturing luxury vinyl tiles (LVT). WO2018060189 (AGFA NV) discloses said manufacturing method.

Said one or more aqueous pigmented inkjet inks are preferably jetted before or after impregnation of the substrate web (100) with a thermosetting resin.

The printer (200) of the present disclosure is hereby preferably part of a manufacturing line for manufacturing decorative surfaces.

The inkjet printing method preferably comprises the step: applying before step a) on the paper substrate at least one ink-receiving layer containing a polyvinylalcohol polymer and an inorganic pigment, wherein more preferably an outermost ink-receiving layer contains no inorganic pigment or contains a smaller content of inorganic pigment than an ink-receiving layer between the paper substrate and the outermost ink-receiving layer.

The use of the edge bender (203, 204) in a manufacturing line for manufacturing decorative surfaces is also an embodiment of the present disclosure, especially the edge bender with the staggered pair of sliding means (2031, 2041, 2032, 2042) as described under chapter 'Edge bending'.

Manufacturing Decorative Panels

The printed paper substrate in the manufacturing decorative surfaces becomes preferably then a decorative layer of a decorative panel, as decorative surface, which is more preferably selected from the group consisting of flooring,

55 kitchen, furniture and wall panels. Herein the printed continuous substrate web, whether or not cut in sheets, is applied on a core layer, such as a MDF-plate, and optional other layers, such as balancing layer, protective layer or a sound-absorbing layer where after the whole assembly of substrate webs and said one or more layers is heat pressed together.

For example, DPL process (Direct Pressure Laminate) is a known method for manufacturing of decorative panels.

The paper substrate has preferably a porosity according to Gurley's method (DIN 53120) between 8 and 20 seconds.

It is found that the pair of lines (1010, 1020) is not visible anymore in the manufactured decorative panel.

In a preferred embodiment the elongated strips (101, 102) become part of a tongue and/or groove which is applied in the decorative panels which allow the decorative panels to be clicked into one another. The advantage thereof is an easy assembly requiring no glue. A shape of the tongue and groove necessary for obtaining a good mechanical join is well-known in the art of laminate flooring, as also exemplified in EP 2280130 A (FLOORING IND), WO 2004/053258 (FLOORING IND), US 2008010937 (VALINGE) and U.S. Pat. No. 6,418,683 (PERSTORP FLOORING).

The tongue and groove profiles are especially preferred for flooring panels and wall panels, but in the case of furniture panels, such tongue and groove profile is preferably absent for aesthetical reasons of the furniture doors and drawer fronts. However, a tongue and groove profile may be used to click together the other panels of the furniture, as illustrated by US 2013071172 (UNILIN).

The image printed on the continuous substrate web (100) is preferably a wood pattern, having nerves. In a preferred embodiment nerves of a printed wood pattern are oriented substantially parallel to the pair of lines (1010, 1020).

The use of the edge bender (203, 204) in a manufacturing line for manufacturing decorative surfaces is also an embodiment of the present disclosure, especially the edge bender with the staggered pair of sliding means (2031, 2041, 2032, 2042) as described under chapter 'Edge bending'.

Core Layers

The core layer is preferably made of wood-based materials, such as particle board, MDF or HDF (Medium Density Fibreboard or High Density Fibreboard), Oriented Strand Board (OSB) or the like. Use can also be made of boards of synthetic material or boards hardened by means of water, such as cement boards. In a particularly preferred embodiment, the core layer is a MDF or HDF board.

The core layer may also be assembled at least from a plurality of paper sheets, or other carrier sheets, impregnated with a thermosetting resin as disclosed by WO 2013/050910 (UNILIN). Preferred paper sheets include so-called Kraft paper obtained by a chemical pulping process also known as the Kraft process, e.g. as described in U.S. Pat. No. 4,952,277 (BET PAPERCHEM).

In another preferred embodiment, the core layer is a board material composed substantially of wood fibres, which are bonded by means of a polycondensation glue, wherein the polycondensation glue forms 5 to 20 percent by weight of the board material and the wood fibres are obtained for at least 40 percent by weight from recycled wood. Suitable examples are disclosed by EP 2374588 A (UNILIN).

Instead of a wood based core layer, also a synthetic core layer may be used, such as those disclosed by US 2013062006 (FLOORING IND). In a preferred embodiment, the core layer comprises a foamed synthetic material, such as foamed polyethylene or foamed polyvinyl chloride.

Other preferred core layers and their manufacturing are disclosed by US 2011311806 (UNILIN) and U.S. Pat. No. 6,773,799 (DECORATIVE SURFACES).

The thickness of the core layer is preferably between 2 and 12 mm, more preferably between 5 and 10 mm.

An embodiment of the present disclosure is a method of manufacturing decorative panels comprising the steps of:

- printing a wood pattern on a paper substrate according to the inkjet printing method of the present disclosure and its preferred embodiments;
- impregnating the printed paper substrate with a thermosetting resin;
- heat pressing the thermosetting resin impregnated printed paper substrate between a core layer and a protective

layer and cut into a decorative panel selected from the group consisting of flooring, kitchen, furniture and wall panels.

Thermosetting Resin

5 The thermosetting resin is preferably selected from the group consisting of melamine-formaldehyde based resins, ureum-formaldehyde based resins and phenol-formaldehyde based resins.

10 Other suitable resins for impregnating the paper are listed in [0028] of EP 2274485 A (HUELSTA).

Most preferably the thermosetting resin is a melamine-formaldehyde based resin, often simply referred to in the art as a 'melamine (based) resin'.

Manufacturing Decorative Corrugated Cardboards

15 The printed paper substrate in the manufacturing decorative surfaces becomes preferably a decorative facing of linerboard of a decorative corrugated cardboard, as decorative surface.

20 In the manufacturing of a decorative corrugated cardboard, the printed continuous substrate web, whether or not cut in sheets, is glued on one or more fluted sheets of paperboard (corrugating medium).

25 Corrugated card board is a preferred packaging material as it is low cost and lightweight, but also has the benefit that corrugated cardboard boxes are stackable, making them easy to store and transport. Corrugated cardboard is a packaging material formed by gluing one or more fluted sheets of paperboard (corrugating medium) to one or more flat sheets (called facings) of linerboard. It comes in four common

30 types: (a) Single face: one fluted sheet glued to one facing (total two sheets). (b) Single wall: one fluted sheet sandwiched between two facings (total three sheets); also called double face or single ply. (c) Double wall: one single-face glued to one single wall so that two fluted sheets are

35 alternatively sandwiched between three flat sheets (total five sheets); also called double cushion or double ply. (d) Triple wall: two single-face glued to one single wall so that three fluted sheets are alternatively sandwiched between four flat sheets (total seven sheets); also called triple ply.

40 The preferred corrugated cardboard in the present invention is single wall or double wall, more preferably single wall corrugated cardboard as this is sufficiently strong and easy to crease. Single face corrugated cardboard generally has insufficient strength to hold the merchandise articles, while triple wall cardboard is often more difficult to crease into a packaging box.

45 The paper used in corrugated card board, such as Kraft paper, has often a brownish colour. In a preferred embodiment of the manufacturing decorative corrugated cardboard the paper substrate as the continuous substrate web (100) has a white colour for enhancing the colour vibrancy of the inkjet inks printed thereon. The white background contributes to the customer experience as the customer regards this as a more luxurious product. Alternatively, the white background may be applied as a layer by coating or printing prior to inkjet printing the image.

50 An embodiment of the present invention is method of manufacturing decorative corrugated cardboards wherein the continuous substrate web (100) is the paper substrate; and wherein said method of manufacturing has an additional step for forming a decorative corrugated cardboard: gluing the printed paper substrate on a fluting sheet of paperboard.

55 The elongated strips (101, 102) may be spread again after printing the image (500) and before gluing on said fluting sheet of paperboard. More preferably the elongated strips (101, 102) are flattened after printing the image (500) and before gluing on said fluting sheet of paperboard.

The invention claimed is:

1. An inkjet printing method on a continuous substrate web, having a pair of edges, the method comprising:

- (a) forming a pair of elongated strips by bending said substrate web along a pair of lines wherein each line is parallel to the pair of edges;
- (b) after bending said substrate web along the pair of lines to provide a bent substrate web, supporting said bent substrate web in a support zone of a printer wherein said pair of elongated strips are oriented below said zone; and
- (c) printing an image on said supported substrate web by an inkjet-printhead of said printer, wherein the support zone is formed on a conveyor belt or a vacuum belt of said printer.

2. The inkjet printing method of claim 1, wherein the pair of elongated strips are formed by a pair of edge bender units of the printer, each having staggered pair of sliding means, and wherein the continuous substrate web is bent between said staggered pair of sliding means which is a support sliding means for supporting said substrate web and a bending sliding means for applying a pressure towards said substrate web along said support sliding means.

3. The inkjet printing method of claim 2, further comprising a step for controlling the width of one of the pair of elongated strips including:

- moving an edge bender unit of said pair of edge bender units across the continuous substrate web for controlling the width of one of the pair of elongated strips.

4. The inkjet printing method of claim 2, further comprising steps for controlling the bending angle at the one of the pair of elongated strips by the edge bender unit including:

- moving the bending sliding means towards the substrate web along the support sliding means in a direction; and/or
- moving said bending sliding means towards said support sliding means in another direction.

5. The inkjet printing method of claim 4, wherein step b) further comprises:

- applying vacuum below the support zone for holding the pair of elongated strips below said zone; and
- optionally applying vacuum for holding down the supported substrate web towards said zone.

6. The inkjet printing method of claim 1, whereby the support zone has a pair of opposite edges and each line of the pair of lines is positioned along an edge of said pair of opposite edges.

5 7. The inkjet printing method of claim 1, wherein the width of each elongated strip of the pair of elongated strips is below 10 cm.

8. The inkjet printing method of claim 7, wherein the support zone is formed on a vacuum belt of the printer.

10 9. A method for manufacturing a decorative surface using the inkjet printing method of claim 1, wherein the continuous substrate web is a paper substrate which has a weight less than 150 g/m² and the image is printed with one or more aqueous pigmented inkjet inks.

15 10. The method for manufacturing a decorative surface of claim 9, wherein the paper substrate has a porosity according to Gurley's method (DIN 53120) between 8 and 20 seconds and the method further comprises:

20 applying before step a) on the paper substrate at least one ink-receiving layer containing a polyvinylalcohol polymer and an inorganic pigment, wherein the image is printed with the one or more aqueous pigmented inkjet inks before or after impregnation with a thermosetting resin.

25 11. The method for manufacturing a decorative surface of claim 10, wherein an outermost ink-receiving layer contains no inorganic pigment or contains a smaller content of inorganic pigment than an ink-receiving layer between the paper substrate and the outermost ink-receiving layer.

30 12. A method of manufacturing a decorative panel comprising the steps of:

35 printing a wood pattern on the paper substrate as claimed in claim 11;

impregnating the printed paper substrate with a thermosetting resin after flattening the pair of strips by spreading said strips; and

heat pressing the thermosetting resin impregnated printed paper substrate between a core layer and a protective layer and cut into the decorative panel selected from the group consisting of flooring, kitchen, furniture, and wall panels.

40 13. A method of manufacturing decorative corrugated cardboards comprising the method of claim 9, wherein the method of manufacturing has an additional step for forming a decorative corrugated cardboard including:

45 gluing the printed paper substrate on a fluting sheet of paperboard.

14. A method of manufacturing a decorative panel comprising the steps of:

printing a wood pattern on the paper substrate as claimed in claim 10;

impregnating the printed paper substrate with a thermosetting resin after flattening the pair of strips by spreading said strips; and

heat pressing the thermosetting resin impregnated printed paper substrate between a core layer and a protective layer and cut into the decorative panel selected from the group consisting of flooring, kitchen, furniture, and wall panels.

55 15. A method for manufacturing a decorative surface using the inkjet printing method of claim 1, wherein the continuous substrate web is a thermoplastic substrate which has a weight less than 150 g/m² and which is based on a material selected from the group consisting of polyvinylchloride (PVC), polypropylene (PP), polyethylene (PE), polyethylene-terephthalate (PET) and thermoplastic poly-

urethane (TPU) and combinations thereof and the image is printed with one or more UV curable inkjet inks.

16. The inkjet printing method of claim **1**, wherein the printing step is a single pass printing method.
